CHILD'S CHAIR

Albert Janesick, Flint, Mich.

Application July 17, 1951, Serial No. 237,261

5 Claims. (Cl. 155—127)

1

This invention relates to children's chairs and more particularly to chairs constructed for preventing a child from either sliding forward in the seat of the chair or raising himself from the seat to a position where he may fall from the chair.

Heretofore, restraining straps have been extensively employed, both in the form of a belt secured to the chair and around the waist of the child, and in a strap attached to the seat and tray of the chair and extending between the legs of a child. Straps, while usually requiring the attachment and detachment thereof when placing or removing a child from the chair, have further proven unsatisfactory due to stretchiness and a tendency to break, and in some instances have caused serious injury to children while they are attempting to get out of the chair. Other attempts have been made by providing between the tray and seat a post that is straddled by the child, but these fail to perform the dual function of preventing forward sliding of a child on the seat and of keeping a child from raising himself from the seat.

It is therefore proposed to provide a novel and improved child's chair having a vertically extending member between a seat and a child-restraining element such as a tray or table of the chair at a location well within the crotch of a child who will straddle said member while seated in the chair, said member restricting the area of the seat rearwardly of said member to such a degree as to render it impossible for a child to raise himself from a seated position.

More specifically, it is an important object of the invention to have said member between the seat and tray in the form of a partition parallel with sides of the chair and of a depth substantially equal to the width of the tray for further restricting turning movement of a child seated in the chair.

Another object of the invention is to provide a child's chair in accordance with the preceding objects wherein the partition is bodily carried by the tray and depends therefrom to a location slightly spaced above the seat for permitting wraps placed over the legs of a child to extend under said partition.

A further object of the invention is to provide a child's chair as outlined above which has the tray thereof adjustable on the arms of the chair for adjusting the tray and partition in unison to different positions relative to the remainder of the chair to allow heavy blankets to be wrapped about the child and to care for children of different sizes.

2

It is also an object of the invention to provide an improvement to children's chairs which is simple and substantial in construction, which can be manufactured economically, and which will be thoroughly efficient and practical in use.

These, together with various auxiliary features and objects of the invention which will later become apparent as the following description proceeds, are attained by the present invention, 10 a preferred embodiment of which has been illustrated, by way of example only, in the accompanying drawings, wherein:

Figure 1 is a perspective view of the chair showing a child seated therein, and with the 15 lower ends of the chair legs broken away;

Figure 2 is a side elevation of same with the child removed;

Figure 3 is a top plan of the chair showing the 20 forward ends of the arms and partition in dotted lines; and

Figure 4 is a front elevation of the tray and 25 partition removed from the remainder of the chair.

Referring now more specifically to the accompanying drawings, wherein like numerals designate similar parts throughout the various views, there is indicated at 10, a child's chair which, for the purpose of illustration, is shown as a high chair having a seat 11, legs 12, back 13, arms 14 supported by posts 15, and a tray 16 for food or playthings. The tray 16 extends across the arms 14 and is adjustably supported thereon in forward and rearward directions by brackets 17 on said tray sliding on bars 18 attached to the arms, there being pins 19 carried by the brackets and 30 engaging into spaced holes in the bars for holding the tray in adjusted position.

Attached to the underside of the tray 16 substantially midway of its length and depending therefrom is a partition 20 which terminates 35 slightly short of contact engagement with the upper surface of the seat 11, as indicated by the numeral 21 in Figure 2. The partition is rigidly secured to the tray and may, in the manufacture, be formed as one piece providing a T-shaped unit 40 with relatively wide, vertical and horizontal surfaces of substantially the same width. The rear edge 22 of the partition 20 is slightly angled forwardly as it extends downwardly, and both said rear edge and the forward edge 23 are rounded 45 for removal of sharp corners.

When the tray 16 is properly adjusted with the rear edge thereof either adjacent or in contact with a child's body, the rear edge 22 of the partition will be in a like position well within the 50 crotch of the child thus rendering it impossible

for the child to withdraw his leg to a position to engage his foot on the rear edge of the partition to raise himself from the seat. The width of the partition from the rear edge 22 to the front edge 23 relative to size of the seat 11 and locations of the back 13 and arm-supporting posts 15 prevent a child from turning in the seat to a position where one leg projects across the front of the partition which would allow the partition, as shown in Figure 1.

While the partition prevents a child from either sliding forward in the seat or raising himself from the seat to a position where he may fall from the chair, it does not restrain the child to any annoying degree. The child can straighten his legs and raise his knees to the level of the undersurface of the tray and can turn his body far enough to see in all directions. See Figure 1.

Should it be desired to attach the improved partition to the underside of a non-adjustable swinging tray pivoted to the back and resting upon the arms of the chair, it may, in some instances, require that the partition be adjustable relative to the tray.

While I have shown and described the improved partition as associated with a high chair having a tray for food and playthings, it is to be understood that the idea may be employed on any other type of infant's or child's seat where a bracket or any other element is used to limit forward motion of the child in the seat.

In view of the foregoing description, taken in conjunction with the accompanying drawing, it is believed that a clear understanding of the construction, operation, and advantages of the device will be quite apparent to those skilled in this art. A more detailed description is accordingly deemed unnecessary.

It is to be understood, however, that even though there is herein shown and described a preferred embodiment of the invention, various changes may be made without departing from the spirit and full intentment of the invention.

What is claimed is:

1. A child's chair comprising a seat, a back, arms attached to said seat and back; a child-retaining element extending across said arms and spaced above the forward portion of said seat, and a partition bodily carried by said retaining element arranged substantially midway between and parallel with said arms, said partition being located above the forward portion of said seat and has the lower portion of the rear edge thereof adjacent said seat substantially midway of the depth of said seat.

2. A child's chair comprising a seat, a back, arms attached to said seat and back; a child-retaining element extending across said arms and spaced above the forward portion of said

seat, and a partition bodily carried by said retaining element arranged substantially midway between and parallel with said arms, said partition being located above the forward portion of said seat and has the lower portion of the rear edge thereof adjacent said seat and substantially midway of the depth of said seat, said partition terminating short of contact engagement with said seat.

3. A child's chair comprising a seat, a back, arms attached to said seat and back, a child-retaining element extending across said arms and spaced above the forward portion of said seat, and a vertical partition member in the space between said child-retaining element and forward portion of said seat and arranged substantially parallel to said arms, said partition having the rear edge thereof located substantially midway of the depth of the seat and its forward edge located substantially at the forward edge of said seat.

4. A child's chair comprising a seat, a back, arms attached to said seat and back, a tray extending across and supported by said arms and spaced above the forward portion of said seat, a vertical partition of substantially the depth of said tray depending from and bodily carried by said tray and arranged substantially midway between and parallel with said arms, said partition terminating above said seat, and adjustable means for positioning said tray and partition forwardly and rearwardly on said arms and over the forward portion of said seat as a unit relative to the remainder of the chair.

5. A child's chair comprising a seat, a back, arms attached to said seat and back, a tray extending across and supported by said arms and spaced above the forward portion of said seat, a vertical partition of substantially the depth of said tray bodily carried by said tray and arranged substantially midway between and parallel with said arms, and adjustable means for positioning said tray and partition forwardly and rearwardly on said arms as a unit relative to the remainder of the chair, said vertical partition being above and terminating short of contact engagement with the top surface of the forward portion of said seat and having the rear edge thereof angled slightly from a vertical plane in a direction extending forwardly as it extends downwardly to an adjustable location substantially midway of the depth of said seat.
